UNITED STATES PATENT OFFICE.

CHARLES LIPPINCOTT AND JAMES PATTERSON, OF PHILADELPHIA, PA.

DESIGN FOR SODA-WATER APPARATUS.

Specification forming part of Design No. **6,542**, dated April 1, 1873; application filed March 19, 1873.

To all whom it may concern:

Be it known that we, CHARLES LIPPINCOTT and JAMES PATTERSON, both of the city and county of Philadelphia, State of Pennsylvania, have invented a Design for Soda-Water Apparatus, of which the following is a specification:

The soda-water apparatus which forms the subject of our design is clearly illustrated by the figure in the accompanying drawing.

It is hexagonal in shape, and has at each corner a vertical column, *a*, with rounded shaft-base and capital, the bases being joined by a molding, *b*, and the capitals being surmounted by small urns or vases, *c*. Each of the sides of the apparatus has a central panel, *d*; and at the top of each of the said sides is an elaborate molding, *e*, on which urns, statues,

or other ornaments may be placed. The apparatus is surmounted by a glass-covered fountain, *f*, of which there may be one or more. The apparatus has the usual draft-tubes and sirup-faucets.

We claim—

The design for a soda-water apparatus, substantially as described, and as illustrated in and by the accompanying drawing.

In testimony whereof we have signed our names to this specification in the presence of two subscribing witnesses.

CHAS. LIPPINCOTT.
JAMES PATTERSON.

Witnesses:

WM. A. STEEL,
HUBERT HOWSON.
